UNITED STATES PATENT OFFICE.

OLIVER P. MOORE, OF SPOKANE, WASHINGTON.

OIL-BURNING SMELTING-FURNACE.

1,153,561.

Specification of Letters Patent. Patented Sept. 14, 1915.

Application filed May 21, 1915. Serial No. 29,502.

To all whom it may concern:

Be it known that I, OLIVER P. MOORE, a citizen of the United States, residing at Spokane, in the county of Spokane and State of Washington, have invented a new and useful Oil-Burning Smelting-Furnace; and I do hereby declare the following to be a full, clear, and exact description of the invention, such as will enable others skilled in the art to which it appertains to make and use the same.

This invention relates to an oil burning smelting furnace, and one of the objects of the invention is to provide an apparatus of this character for pre-heating and de-oxidizing the ore before entering the smelting chamber, by permitting the hot gases to be drawn through the stack of the furnace by means of natural or mechanical draft.

Another object of the invention is to provide a system of flues under the base of the smelting chamber, so that a down draft is provided for heating the bottom of the chamber, as well as the outlet for the heat gases, thereby giving full control of the heat in the preheating and reduction chamber.

Another object of the invention is that by this preheating and deoxidation of the ore, the furnace will accomplish all the necessary chemical re-actions, with a corresponding low fuel consumption, and furthermore all the heat will be utilized.

In practical fields the details of construction may necessitate alterations, falling within the scope of what is claimed.

The invention comprises further features and combination of parts, as hereinafter set forth, shown in the drawings and claimed.

In the drawings, Figure 1 is a vertical sectional view through the improved furnace constructed in accordance with the invention. Fig. 2 is a side elevation. Fig. 3 is a vertical sectional view at right angles to Fig. 1.

Referring more especially to the drawings, 1 designates the base structure of the furnace, which may be of any suitable shape or contour and provided with a rising preheating and reduction stack, which may likewise be any suitable shape, preferably round or square, and smaller than the base. The stack 2 is provided with a preheating and reduction chamber 3. The upper portion of the stack has an opening 4, in which the chimney stack (not shown) may be connected. A suitable feeding hopper 5 is fixed

to the upper portion of the stack 2, there being gate openings 6 to permit the ore to pass from the hopper 5 into the chamber 3. The base structure of the furnace is provided with a smelting chamber 7, there being a contracted passage or flue 8, which communicates between the preheating and reduction and smelting chambers. Suitable pipes 9 extend through the wall of the stack as shown clearly in Fig. 1, and designed to receive their supply of air from any suitable source (not shown), for conveying the air into the passage 8. It is to be observed that the lower portion of the preheating and reduction chamber is contracted, and mounted in bearings to rock or oscillate partially are hollow grate rods 10 having hollow grate bars or arms 11. One end of each of the grate rods 10 is provided with a lever 12, whereby the rods may be oscillated or rocked, for governing the ore in its flow through the passage 8. These grate rods as shown at 13 have connected to them conduits, receiving cool air or water from any suitable source of supply, whereby the grate rods and bars may be maintained cool. A third grate rod 14 is mounted in bearings of the stack, and which is hollow, and, as shown in Fig. 1, is disposed intermediate the grate rods 10. This grate rod 14 is also provided with grate bars or arms 15, which extend at right angles to each other, so as to project toward the opposite walls 16 of the lower tapered part of the chamber 3, so as to further control the ore in its flow from the chamber 3 into the passage 8. The grate rod 14, as shown at 17 is connected to a suitable conduit, which receives cold air or water, for maintaining the rods and the bars or arms 15 cool. The air or water passes out of the grate rods 10 and 15, at their ends opposite the ends where the air and water enters. The smelting chamber 7 is provided with a plurality of flues 18 extending from the chamber 19 in opposite directions, then upwardly as at 20, to pass out at 21, so that a down draft from the reduction chamber through the passage 8 into the smelting chamber 7 may pass through the flues 18 for heating the bottom of the smelting chamber, and exit through the second outlet opening 22, which may be connected to the chimney stack (not shown), in any suitable manner (not shown). The base or bottom of the smelting chamber is provided with a suitable furnace lining 23, con-

structed of any suitable material, for instance, fire clay or the like.

Supported in any suitable manner in recesses 25 of the base structure are the usual oil burners 26, receiving their oil supply through the pipes 27, from any suitable source (not shown). These pipes 27 are provided with suitable valves 28 to control the oil in its flow. Connected to the burners 26 are steam or air pipes 29 having suitable valves 30 for controlling the air or steam. The burners are provided with the usual nozzles 31, which extend through the wall of the base structure, in order to project the heat into the smelting chamber, and in contact with the ore in the bottom of the chamber for smelting the same. By virtue of the air or steam pipes, the oil in the burners is mechanically mixed with the proper amount of air in order to produce the best and proper combustion. One side wall of the smelting chamber 7 has an outlet passage or tap 33, for drawing off the slag from the top of the molten metal in the chamber 7. Below the tap or opening 33 is a second opening or tap 34 for drawing off the molten metal. These taps or openings may be plugged in the usual manner (not shown) by means of clay plugs.

When using the furnace, the preheating and reduction chamber is filled with ore, including a proper amount of lime and carbon. The hot gases from the smelting chamber are drawn into and through the preheating and reduction chamber by means of natural or mechanical draft, thereby preheating and deoxidizing the ore prior to entering the smelting chamber. The ore is held in the preheating and reduction chamber by means of the water or air cooled grate, which will allow the free passage for the hot gases. By rocking or oscillating the grate bars 10 and 14, any desired amount of ore is allowed to pass through the passage 8 into the smelting chamber, into which and upon the ore, the heat from the oil burners, one upon each side of the smelting chamber, is projected. Through ebullition or boiling in smelting, the ore is distributed over the whole surface of the smelting zone, thereby exposing the greatest possible surface of the ore to the action of the heat. Through the system of flues under the base of the smelting cham-

ber enables a down draft, for heating the bottom of said chamber, the heat gases passing off through the passage 22, thereby giving full control of the heat in the preheating and reduction chamber. 55

The invention having been set forth, what is claimed as new and useful is:— 60

1. In a furnace, a refining chamber in communication at the top with a pre-heating chamber; burners at opposite sides of the refining chamber adjacent the top to throw flames over the surface of the bath; flues leading from the side of the refining chamber from points just below the burners and connecting with a discharge flue underneath the floor of such chamber, the relation between the flues and the openings being such as to provide a partial upwardly draft into the pre-heating chamber; and a discharge 65 extending transversely of the furnace and under the floor of the refining chamber for removing the waste gases. 70

2. In a furnace, a refining chamber having at the top an opening of communication with a pre-heating chamber; burns at opposite sides of the refining chamber adjacent the top thereof to throw flames toward each other and over the surface of the bath; a discharge chamber substantially centrally below the floor of the refining chamber and extending transversely thereof, and having a discharge opening at one side of the furnace; a plurality of flues leading from each side of the refining chamber from a point just below the burners and curving downwardly, inwardly and beneath the floor of the refining chamber, and toward the opposite flues, and communicating with the discharge chamber; the relation between the flues, the discharge chamber and its discharge opening and the opening of communication being such as to provide a partial upward draft into the preheating chamber, said flues constituting means to carry off the waste gases through the discharge chamber and its opening. 80 85 90 95

In testimony whereof I have signed my name to this specification in the presence of two subscribing witnesses.

OLIVER P. MOORE.
